UNITED STATES PATENT OFFICE

JOSEPH E. EVANS, OF BEDFORD, INDIANA, ASSIGNOR TO EVANS ELEVATOR EQUALIZER COMPANY, OF BEDFORD, INDIANA, A CORPORATION OF INDIANA

SUSPENSION DEVICE FOR EQUALIZING THE STRAIN ON ELEVATOR CABLES

Application filed September 16, 1929. Serial No. 392,098.

The present invention relates to a device for equalizing the strain upon a group of cables, such as those commonly used to suspend an elevator car used for transferring 5 passengers or freight from one floor of a building to another. In the type of elevators most widely used the group of hoisting cables, usually about six in number, though a greater or less number may be employed, track in a corresponding number of 10 grooves formed in a suspension pulley or drum at the top of the elevator shaft, the weight of the car being according to usual practice counterbalanced by weights also connected to the suspension cables. Because of 15 unavoidable variations in manufacture the cables are liable to stretch unequally, and in case of replacement of one or more cables, because of variations in wear and stretch as between the new and old cables, as well as variations 20 in the diameter of the grooves in the pulleys engaged by the cables, the cables do not, if rigidly connected to the car, at all times in the travel of the car, especially in the case of tall buildings, sustain an equal load, and the cable upon which the greatest load 25 is thrown is subject to the greatest wear and liability of breakage. My present invention relates to a type of suspension device in which the load of the car is sustained and equalized 30 by a body of liquid, preferably oil, interposed between a series of inter-communicating cylinders connected to the car, and a series of pistons in said cylinders connected 35 severally with the hoisting cables. The object of my invention is the provision of a suspension device of the type which in the construction and arrangement of its mechanical parts and members shall be better suited and 40 adapted to perform the functions and accomplish the results for which it is designed than previous equalizers of the type in question known to me. With this object in view I have designed and invented the novel suspension device hereinafter described in detail, the essential elements of my invention 45 being more particularly pointed out in the appended claims.

In the drawings, Figure 1 is a side elevation, on a small scale, showing in outline an

elevator car and portions of the supporting structures and lifting apparatus with my novel equalizing device applied thereto;

Fig. 2 is what I will term a side view of the device, in a larger scale;

Fig. 3 is an end view of the same;

Fig. 4 is a top plan view of the same, the anchor bolts secured to the cables being shown in section and parts of the supporting plates of the car frame being indicated;

Fig. 5 is a vertical section extending axially of one of the cylinders and the piston therein on the dotted line 5-5 of Fig. 4, parts of the structure being shown in elevation; and

Fig. 6 is a top plan view of the top plate of the cylinder frame.

Like reference characters indicate like parts on all the figures of the drawings.

Referring to Fig. 1, which illustrates an ordinary and well known arrangement of elevator mechanism, the suspension or hoisting cables A, which by means of my novel equalizing device, indicated generally by the reference letter B, are severally connected at 70 one end to the elevator car C, severally engage alternate grooves (not shown) of the suspension pulley D; then grooves of the idler pulley E and then pass around the pulley D again, in the intermediate or adjacent grooves 75 of such pulley, the other ends of the cables being operatively connected with the counterweight and hoisting mechanism, not illustrated.

Describing now in detail the construction 85 of the device B itself, the cylinder frame attached to the car includes a top plate 1, and a bottom plate 2, between which are interposed the tubular cylinder members 3, the top and bottom plates being connected by 90 clamping bolts to clamp the cylinders between them. Preferably for convenience of assemblage, two of the clamping bolts, as the bolts 4, (or if desired a greater number) engage threaded seats in the bottom plate, 95 while the remaining bolts, in the present instance the bolts marked 5, six in number, are not threaded in either plate.

The top plate 1 is formed with cylindrical seats 6 to receive the upper ends of the cylin- 100

their lower ends supporting the lower ends of the pistons.

2. A suspension device for connecting an elevator car to a group of hoisting cables comprising a cylinder frame secured to said car and a plurality of inter-communicating oil-filled cylinders in said frame, a corresponding plurality of pistons in said cylinders, and a plurality of piston frames including shackle rods slidingly mounted in said cylinder frame, said piston frames being connected at their upper ends to the hoisting cables and having cross-bars at their lower ends supporting the lower ends of the pistons, said pistons being free to move upon the supporting faces of said cross-bars.

3. A suspension device for connecting an elevator car to a group of hoisting cables comprising a cylinder frame secured to said car, a plurality of inter-communicating oil-filled cylinders in said frame, a corresponding plurality of pistons in said cylinders, a plurality of piston frames including shackle rods slidingly mounted in said cylinder frame, said piston frames being connected at their upper ends to the hoisting cables and having cross-bars at their lower ends supporting the lower ends of the pistons, and buffer springs interposed between said cross bars and said cylinder frame.

4. A suspension device for connecting an elevator car to a group of hoisting cables comprising a cylinder frame secured to said car, a plurality of inter-communicating oil-filled cylinders in said frame, a corresponding plurality of pistons in said cylinders, a plurality of piston frames including shackle rods slidingly mounted in said cylinder frame, said piston frames being connected at their upper ends to the hoisting cables and having cross-bars at their lower ends supporting the lower ends of the pistons, and buffer springs interposed between said cross bars and said cylinder frame, said buffer springs being normally idle and arranged to be stressed upon movement of said pistons and piston frames to a higher position relative to said cylinders.

5. A suspension device for connecting an elevator car to a group of hoisting cables, said device comprising a cylinder frame secured to the car including an orificed top plate formed with cylinder seats and an orificed bottom plate formed with open cylinder seats and a plurality of cylinders seated in said top and bottom plates and clamping bolts arranged to clamp said top and bottom plates to said cylinders, said top plate being formed with passages providing communication between said cylinders, a plurality of pistons in said cylinders, and a plurality of piston frames each having a pair of shackle rods slidingly mounted in aligned orifices in said top and bottom plates of the cylinder frame, said piston frames being each pro-

vided with a cross-bar secured to the lower ends of said shackle rods and arranged to support the lower end of the associated piston.

6. A suspension device for connecting an elevator car to a group of hoisting cables, said device comprising a cylinder frame including an orificed top plate secured to the car and an orificed bottom plate formed with open cylinder seats and a plurality of interposed cylinders and clamping bolts arranged to clamp said top and bottom plates to said cylinders, said top plate being formed with passages providing communication between said cylinders, a plurality of pistons in said cylinders, and a plurality of piston frames each having a pair of shackle rods slidingly mounted in aligned orifices in said top and bottom plates of the cylinder frame, said piston frames being each provided with a cross-bar secured to the lower ends of said shackle rods and arranged to support the lower end of the associated piston.

7. A suspension device for connecting a group of hoisting cables to an elevator car having a pair of spaced horizontally disposed supporting plates, said device including an orificed top plate extending over and resting upon said supporting plates and also including an orificed bottom plate and a plurality of interposed cylinders and clamping bolts disposed between said supporting plates, said clamping bolts being arranged to clamp said bottom plate and interposed cylinders to said top plate and said cylinders being in communication at their upper ends, a plurality of pistons in said cylinders, piston frames connected to said hoisting cables and arranged to support said pistons, a pair of clamping plates at opposite ends of the device extending underneath said supporting plates, and clamping bolts engaging said top plate adjacent its opposite ends for clamping said top plate to said supporting plates.

8. A suspension device for connecting a group of hoisting cables to an elevator car having a pair of spaced horizontally disposed supporting plates, said device including an orificed top plate extending over and resting upon said supporting plates and also including an orificed bottom plate and a plurality of interposed cylinders and clamping bolts disposed between said supporting plates, said clamping bolts being arranged to clamp said bottom plate and interposed cylinders to said top plate and said cylinders being in communication at their upper ends, a plurality of pistons in said cylinders, piston frames connected to said hoisting cables and arranged to support said pistons, and clamping means at opposite ends of said suspension device engaging said top plate and extending underneath and engaging said supporting plates.

9. A suspension device for connecting a group of hoisting cables to an elevator car

having a pair of spaced horizontally disposed supporting plates, said device including an orificed top plate extending over and resting upon said supporting plates and also including an orificed bottom plate and a plurality of interposed cylinders and clamping bolts disposed between said supporting plates, said clamping bolts being arranged to clamp said bottom plate and interposed cylinders to said top plate and said cylinders being in communication at their upper ends, a plurality of pistons in said cylinders, piston frames connected to said hoisting cables and arranged to support said pistons, a pair of clamping plates at opposite ends of the device extending underneath said supporting plates, and clamping bolts engaging said top plate adjacent its opposite ends for clamping said top plate to said supporting plates, the sides of said top plate and the ends of said clamping plates being formed with retaining lugs extending upon the outer faces of said supporting plates.

10. A suspension device for connecting an elevator car to a group of equally spaced elevator cables arranged to track in the grooves of a common supporting pulley, said device comprising a cylinder frame secured to the car and a plurality of intercommunicating oil-filled cylinders in said frame, said cylinders being disposed in staggered arrangement in two parallel adjacent planes, a corresponding plurality of pistons in said cylinders, and a plurality of rectangular piston frames, each frame including an upper cross-bar centrally secured to an associated hoisting cable and secured at its ends to a pair of shackle rods slidingly mounted in said cylinder frame, and a lower cross-bar supporting the lower end of an associated piston, the planes of the piston frames extending in different directions alternately at angles to the two planes in which the pistons and cylinders are arranged.

11. A suspension device for connecting an elevator car to a group of hoisting cables comprising a cylinder frame secured to said car and a plurality of inter-communicating oil-filled cylinders in said frame corresponding in number to the number of hoisting cables, a corresponding plurality of pistons in said cylinders, and a corresponding plurality of piston frames including shackle rods slidingly mounted in said cylinder frame, said piston frames having cross-bars at their upper ends individually connected to the hoisting cables and having cross-bars at their lower ends individually supporting the lower ends of the pistons.

12. A suspension device for connecting an elevator car to a group of hoisting cables, said device comprising a cylinder frame secured to the car including an orificed top plate formed with cylinder seats and an ori-

ficed bottom plate formed with open cylinder seats and a plurality of cylinders corresponding in number to the number of hoisting cables seated in said top and bottom plates and clamping bolts arranged to clamp said top and bottom plates to said cylinders, said top plate being formed with passages providing communication between said cylinders, a plurality of pistons severally arranged in said cylinders, and a corresponding plurality of piston frames each having a pair of shackle rods slidingly mounted in aligned orifices in said top and bottom plates of the cylinder frame, said piston frames being each provided with a cross-bar secured to the lower ends of said shackle rods and arranged to support the lower end of the associated piston.

In testimony whereof, I have subscribed my name.

JOSEPH E. EVANS.
